FIG. 1 is a front elevational view of a wall plate or similar article embodying our new design;

FIG. 2 is a side elevational view thereof;

FIG. 3 is a bottom plan view of the wall plate or similar article of the wall plate of FIG. 1;

FIG. 4 is a back elevational view thereof;

FIG. 5 is a side elevational view of the side opposite that shown in FIG. 2;

FIG. 6 is a top plan view thereof;

FIG. 7 is a detail cross-sectional view of a portion of the wall plate of FIG. 1 taken along the line 7—7 of FIG. 1 and illustrating the three dimensional contouring of the wall plate or similar article ornamentation as well as the relationship of this contouring to the decorative matter imprinted on the surface of the wall plate or similar article.

The characteristic feature of our design resides in the appearance features of the contoured and imprinted wall plate or similar article as shown and described.

We claim:

The ornamental design for wall plate or similar article, as shown and described.
